UNITED STATES PATENT OFFICE.

OSWALD DUDA, OF HOUSTON, TEXAS, ASSIGNOR TO REED ROLLER BIT COMPANY, A CORPORATION OF TEXAS.

LUBRICATOR FOR DEEP-WELL DRILLS AND THE LIKE.

Application filed June 8, 1920. Serial No. 387,478.

To all whom it may concern:

Be it known that I, OSWALD DUDA, a citizen of the United States, and resident of Houston, Texas, have invented certain new 5 and useful Improvements in Lubricators for Deep-Well Drills and the like, of which the following is a specification.

The invention relates to means for lubricating the cutters of deep well rotary drilling 10 apparatus or the like, and concerns a simple and efficient means whereby the lubricant may be positively forced to the parts to be lubricated.

The invention consists in the feature and 15 combination and arrangement of parts hereinafter described and particularly pointed out in the claims.

In the accompanying drawings—

Figure 1 is a vertical section of so much 20 of a rotary drilling apparatus as is necessary to illustrate my invention in connection therewith.

Figure 2 is a plan view of the propellor or rotor.

Figure 3 is a plan view of the oil forcing piston.

Figure 4 is a detail of the protector or strainer of Figure 1.

Figure 5 is a plan view of a modified 25 form of propeller showing fewer blades than in the form illustrated in Figure 2.

Figure 6 is a plan view of a portion of the spider.

Figure 7 is a diagram of the relative position of the wings of the propeller protector or strainer, the propellor and the spider.

In these drawings 1 indicates a section 30 of the drill stem screw threaded at its upper end for connection to the section next above it. 2 indicates a form of coupling which is used to connect the lower drill stem section 1 with the head 3 of the drill or other device with which the lubricator 45 is to be employed.

The lubricator comprises a cylindrical container 4 having a bottom 5 perforated at 5^a for the discharge of the lubricant.

This lubricator chamber or reservoir is 50 connected with the head 3 of the apparatus by a cup shaped member 6 into which the body 4 is screwed, and this connecting member has a screw threaded nipple 7 forming the connection with the head 3, this nipple

being hollow to direct the lubricant to distributing conduits, one of which is shown at 8, leading to the parts to be lubricated.

Within the lubricant containing chamber 4 there is a piston made up of a member 9 having a central body portion provided 60 with a screw threaded opening, and a flange 9^a on which the packing 10 is held by the disc 11 which in turn is held by the nut 12 screw threaded on to the upper end of the member 9. The screw threaded opening of the member 9 receives the screw threaded rotary shaft or rod 13 so that when the shaft is rotated the piston will be forced down to positively press the lubricant through the openings 5^a and conduits 70 8 to the parts to be lubricated.

This rotary shaft is journalled in the bottom 5 of the lubricant container and also in the top 14 thereof which is screw threaded into the cylindrical body part 4. 75

In the illustrated embodiment of my invention the rotary shaft is turned by a propeller or rotor 15 keyed thereto at 16 but this shaft may be otherwise rotated. This propeller has inclined blades as shown in 80 Figure 2 and these are acted on by the water flowing down through the drill stem. This water after acting on the propeller passes down through the annular space 17 between the drill stem and the lubricant 85 container and finds an outlet through a passage or passages 18 formed through the drill head. This water flushes the hole and clears the cutters.

A vent is provided at 19 to prevent the 90 formation of a vacuum above the piston when the latter is positively moved downward through the operation of the screw threaded shaft.

The shaft 13 has its lower portion 13' 95 formed of reduced diameter and without screw threads, so that when the piston 9 reaches its lowest limit it will free itself from the screw threaded portion of the said shaft and hence will not be further 100 acted on thereby. This will prevent strain and damage to the parts.

A strainer or grid 20 is arranged above the propeller for collecting any débris which may have found its way into the drill stem, such for instance as a piece of pump packing. This will be caught by the grid and prevented from clogging the propeller 105

blades or interfering with their proper functioning.

At 21 I show a spider surrounding the upper end of the lubricant holder and serving to brace this upper end from the wall of the drill stem.

The relative inclination of the blades of these members, i. e., grid, propeller and spider is illustrated in the diagram Fig. 7, 10 the direction of flow of the water being indicated by the arrows.

The shaft 13 has collars 22 pinned thereto, or other fastenings, which hold the shaft in place.

15 The grid as in Figure 1 is conveniently mounted on the upward extension of the shaft 13, which is prolonged for this purpose.

The grid is not rigidly secured to this 20 shaft.

The piston 9 is split longitudinally into two halves as indicated by the line *x* in Figure 3.

I do not limit myself to the use of the grid 25 20 or the spider 21, as these features can be omitted.

It will be seen from the above that in carrying out my invention I preferably utilize the flow of the flushing water through 30 the apparatus to operate means which controls the feed of the lubricant from the reservoir to the bearing of the cutter or cutters, and while the means for utilizing this flow of water may assume different 35 forms, the particular form which I show as exemplifying my invention includes a rotor which is turned by the flow of the water and imparts its movement to a plunger.

40 As will be understood by those skilled in this art, in the use of a drill provided with a lubricant reservoir in which a piston is located designed to be advanced, to feed the lubricant therefrom, by the pressure of 45 the flushing fluid upon the upper side thereof, it is essential to provide at the upper end of the reservoir means for arresting the upward movement of the piston, or otherwise it, with the lubricant in the reservoir, 50 would be ejected from the upper end of the reservoir, due to the back pressure on the drill head when it is being lowered into the well, and if the piston were not sufficiently heavy, or weighted, to overcome the difference 55 in specific gravity between the lubricant and the flushing fluid, when the drill is in the well but is not in operation—flushing fluid is not being pumped—the tendency of the lubricant to float would have the same 60 action.

But the provision of the stop at the upper end of the reservoir does not prevent the lubricant rising in the reservoir, due to either of the aforesaid causes, with a consequent displacement of the lubricant at the

bearings of the cutter, and in the lower part of the reservoir, by the dirty or gritty flushing fluid.

This results in premature wearing of the 70 bearings.

My invention completely overcomes this very serious objection, due to the positive feed of the piston in the reservoir, which will advance the lubricant towards the bearing to be lubricated during the cutting action 75 of the drill, and will prevent at all times, and under all conditions which exist when the tool is in the well, a substantial movement of the lubricant in a reverse direction, or the displacement of any substantial part 80 thereof from the bearings of the cutters.

I claim—

1. A tool for boring deep wells comprising a member carrying rotary cutting elements, a stem carrying said member and through 85 which flushing fluid flows when the drill is in operation, a lubricant reservoir, a part operated by the flow of flushing water and means actuated thereby to effect the feed of the lubricant from the reservoir 90 to the bearings of said cutting elements.

2. A tool for boring deep wells comprising a member carrying rotary cutting elements, a stem carrying said member and through 95 which flushing fluid flows when the drill is in operation, a lubricant reservoir, a rotor operated by the flow of flushing water and means actuated thereby to effect the feed of the lubricant from the reservoir to the bearings of said cutting elements. 100

3. A tool for boring deep wells comprising a member carrying rotary cutting elements, a stem carrying said member and through 105 which flushing fluid flows when the drill is in operation, a lubricant reservoir within the drill stem, a plunger for feeding the lubricant from the reservoir to the bearings of the cutting elements and means operated by the flow of the water for moving the plunger, substantially as described. 110

4. A rotary tool for boring deep wells comprising a member carrying rotary cutting elements, a stem carrying said member for rotating the same, and through which the flushing fluid passes to the cutters, a lubricant reservoir in communication with the bearings of the cutting elements, a plunger in the reservoir, and a rotary member located in the stem and which is rotated by contact of the flushing fluid therewith for 115 effecting the feed of the plunger for forcing the lubricant from the reservoir, substantially as described. 120

5. In combination in deep well rotary drilling apparatus, a drill stem, a drill head, a lubricant container in communication with the parts to be lubricated, and arranged axially of the drill stem leaving an annular passage between it and the stem for the 125 passage of flushing water, a member oper- 130

ated by the flow of said water and means for feeding lubricant from said container operated from said member, substantially as described.

5 6. In combination in a deep well rotary drilling apparatus, a drill stem, a drill head, a lubricant container mounted axially within the drill stem leaving an annular passage between itself and the drill stem for the flow 10 of flushing water, a rotor above the lubricant container turnable about the axis of the stem and having its blades reaching across the annular passage to be acted on by the flushing water, and means operated by said 15 rotor for feeding lubricant from the container to the parts to be lubricated, substantially as described.

7. In combination in a tool for boring deep wells, a member carrying rotary cutting elements, a stem carrying said member and through which flushing fluid flows when the drill is in operation, a lubricant reservoir, a bladed rotor to be turned by the flow of the flushing water, means actuated thereby for feeding lubricant from the reservoir and means within the stem for deflecting the flushing water upon the blades of the rotor.

8. In combination in a tool for boring deep wells, a member carrying rotary cutting elements, a stem carrying said member and through which flushing fluid flows when the drill is in operation, a lubricant reservoir, a bladed rotor to be turned by the flow of the flushing water, means actuated thereby for feeding lubricant from the reservoir, and a grid above the rotor to protect the same, said grid having inclined water directing surfaces to deflect the water from its straight course onto the blades of the rotor 40 which are inclined oppositely in respect to said surfaces.

9. In combination, in a tool for boring deep wells, a member carrying rotary cutting elements, a stem carrying said member and through which a flushing fluid flows when the drill is in operation, a lubricant reservoir, a bladed rotor to be turned by the flow of the flushing water, means actuated thereby for feeding lubricant from the reservoir, and spacing means between the upper end of the reservoir and the drill stem, adjacent and below the rotor having inclined surfaces for deflecting the water from its straight course, the inclination of said surface being in a direction opposite to that of the blades of the rotor.

10. A lubricator for deep well rotary drilling apparatus comprising a lubricant container within the drill stem and having 60 an outlet to supply the lubricant to the parts to be lubricated, a piston in the container, a screw threaded rotary shaft engaging the piston for advancing the same to force the lubricant and a propeller member rotated 65 by the water passing through the drill stem

and connected to the screw shaft for rotating the same, substantially as described.

11. A tool for boring deep wells comprising a drill-bit carrying rotary roller cutters, a drill-stem having the drill-bit secured to the lower end thereof, and through which a flushing fluid flows when the drill is in operation, a lubricant reservoir located in the drill-stem, a part outside of the reservoir operated by the flow of the flushing water, and means actuated thereby for effecting the feed of the lubricant from the reservoir to the bearings of the cutters.

12. In combination with a hollow stem and head of a deep well drilling apparatus, a lubricant container arranged coaxially with the drill stem, mounted on the head, and having an annular space between it and the stem, a screw threaded shaft arranged within the container, a piston moved thereby for forcing the lubricant and a propeller member on the upper end of the shaft above the container, rotated by the water passing down through the stem for rotating the shaft and advancing the piston to force the lubricant to the parts to be lubricated.

13. In combination with a hollow drill stem, a lubricant container within the stem, a piston within the container divided into sections and a screw passing between the sections of the piston and means for rotating the screw by the water flowing through the drill stem.

14. In combination with a hollow drill stem and drill head, a lubricant container arranged coaxially within the stem and having a perforated bottom and a top, a screw threaded shaft mounted in the bottom and top, a coupling member of cup shape screw threaded internally and receiving the screw threaded lower end of the lubricant container, said coupling having a hollow nipple screw threaded into the drill head to supply conduits thereof with lubricant, a water passage through the head connecting with the annular water space between the lubricant container and the drill stem, and a propeller on the upper end of the screw shaft rotated by the water passing through the drill stem, substantially as described.

15. In combination with a lubricant container having means for attachment within a hollow drill stem, a propeller to be rotated by the water passing through the hollow drill stem, means operated by the propeller for forcing the lubricant and a grid above the propeller for protecting the latter, substantially as described.

16. In combination with a lubricant container, having means for attachment within a hollow drill stem, a propeller to be rotated by the water passing through the hollow drill stem, means including a shaft having a part thereof threaded, operated by the propeller for forcing the lubricant, and a

- grid above the propeller for protecting the latter, said grid being mounted on the upward extension of the said shaft, substantially as described.
- 5 17. In combination with the drill stem of a rotary deep well drilling apparatus or the like, a lubricant container, a piston therein for forcing the lubricant, a screw shaft for operating the piston, said container having an annular passage for the water between itself and the drill stem, and a propeller on the upper end of the screw threaded shaft having blades overhanging the annular space, substantially as described.
- 10 18. In a tool for boring deep wells and in combination, a drill-stem, a drill-bit secured to the lower end thereof and including a roller cutter, and a lubricant comprising a lubricant holder, a plunger therein, and means actuated by the flushing fluid of the drill during the cutting operation for feeding the plunger in a direction to force the lubricant to the bearings of the cutter, said means including a threaded shaft cooperating with the plunger and a device for rotating the said shaft, substantially as described.
- 15 19. In combination in a tool for boring deep wells, a rotary cutter, a member in which the cutter is journaled, a stem carrying the member at its lower end through which a flushing fluid flows when the drill is in operation, said stem being adapted to be rotated during the operation of the drill, a lubricant reservoir in communication with the bearings of the cutter, a member rotatable independently of the stem and located therein, said member being rotated during the cutting operation of the tool by contact of the flushing fluid therewith, and means actuated thereby for feeding the lubricant from the reservoir to the bearings of the cutter during the cutting operation of the tool, said means also acting to prevent substantial movement of the lubricant in a reverse direction.
- 20 20. In a tool for boring deep wells, a rotary cutter, a member in which it is journaled, a stem carrying said member, a device rotatable independent of the stem and located therein, a lubricant reservoir in communication with the bearings of the cutter, a plunger in said reservoir, means interposed between the device and plunger for advancing the latter as the device is rotated during the cutting operation of the tool, and for retaining the plunger against movement for preventing substantial movement of the lubricant in a direction reverse to that of the direction of feed, said device being rotated by contact of the flushing fluid therewith.
- 25 21. A tool for boring deep wells, comprising a roller cutter, a member carrying the cutter in which it is journaled, a stem carrying said member adapted to be rotated and through which a flushing stream flows for effecting the removal of the detritus, a lubricant reservoir located at the lower end of the tool and having communication with the bearing of the cutter, a member movable lengthwise of the tool during the cutting operation thereof for forcing the lubricant to the parts to be lubricated, and held stationary at other times, a part rotated by contact of the flushing fluid therewith and during the cutting operation of the tool, and connections between said part and member for moving the member during the rotation of said part, and for preventing its movement during the non-rotation of the part.
- 30 22. In a tool of the character described, a lubricant reservoir, a part rotated by contact of the flushing fluid therewith and during the cutting operation of the tool, a piston for forcing the lubricant to the surfaces to be lubricated, and connections between said part and piston for moving the latter lengthwise of the tool during the rotation of said part and maintaining it stationary at other times.
- 35 23. In a roller earth boring drill, a head, rolling cutters thereon, a lubricator barrel attached to said head, there being channels in said head connecting said barrel with the bearings of said cutters, a threaded rotatable shaft mounted centrally in said barrel, a piston screwed on said shaft within said barrel and means to rotate said shaft comprising a turbine wheel secured to said shaft above said barrel and a supporting disc for said shaft above said wheel having radial blades thereon adapted to direct the flushing fluid against the blades of said wheel.
- 40 24. In a roller earth boring drill, a head having roller cutters thereon, and a drill stem attached to said head, in combination with means to lubricate the bearings of said cutters comprising a lubricator barrel on said head within said drill stem and connected by ducts to said bearings, a rotatable shaft in said barrel, a supporting plate for said shaft above said barrel, said plate having inclined radial blades thereon, a turbine wheel on said shaft below said plate, a piston in said barrel having a threaded connection with said shaft whereby the rotation of said turbine will drive said piston downwardly.
- 45 25. In a roller earth boring drill, the combination of a drill head having rolling cutters thereon, and a drill stem on said head, with a lubricator comprising a barrel secured centrally of said head and connected by oil channels to the bearing of said cutters, a perforated disc in the lower end of said barrel, a cap at the upper end thereof, a shaft journaled in said plate and said cap, a turbine wheel on said shaft above said cap, a

piston in said barrel and a driving connection between said shaft and said piston whereby said piston may be forced downwardly.

- 5 26. In a roller earth boring drill, a head, roller cutters thereon, a drill stem on said head, a lubricator barrel on said head within said drill stem, oil connections between the bearings of said cutters and said barrel, a
10 shaft in said barrel, a plate in said drill

stem above said barrel adapted to support said shaft and barrel erect and spaced from said drill stem, a piston in said barrel, a threaded connection between said shaft and piston to move said piston longitudinally of 15 said barrel when said shaft is rotated and turbine means to rotate said shaft.

In testimony whereof I affix my signature.

OSWALD DUDA.
